RAILWAY SIGNALING SYSTEM

Henry S. Young, Wilkinsburg, Pa., assignor to
The Union Switch & Signal Company, Swiss-
vale, Pa., a corporation of Pennsylvania

Application December 31, 1938, Serial No. 248,689

7 Claims. (CL 246—130)

My invention relates to railway signaling systems, and has for an object the provision of novel and improved means for indicating a defective condition existing within such signaling systems.

5 Apparatus embodying my invention is particularly well adapted for indicating that one or more signal lamp filaments of a plurality of signal lamp filaments is burned out or failed. Apparatus embodying my invention further provides means 10 whereby the failure of any one of a plurality of signal lamp filaments effects the display of the indication relating to such defective conditions until such time as the defective signal lamp filament is replaced with an intact filament, and 15 when this is done, the indication is then controlled either automatically or manually to display an indication relating to the normal condition of the system.

I shall describe three forms of apparatus embodying my invention, and shall then point out the novel features thereof in claims.

In the accompanying drawings, Fig. 1 is a diagrammatic view of one form of apparatus embodying my invention when applied to a railway signaling system of the type employed at a railway-highway intersection for warning highway traffic of approaching trains. Figs. 2 and 3 are diagrammatic views showing modified forms of the apparatus shown in Fig. 1, each also embodying my invention.

Similar reference characters refer to similar parts in each of the several views.

Referring to Fig. 1, the reference characters 1 and 1a designate the track rails of a stretch of 35 railway track over which trains move in both directions, and which is intersected at grade by a highway H. Located at such intersection is a plurality of signals adapted to be controlled by trains approaching the intersection for warning highway users of the approaching train. These 40 signals, which are designated by the reference characters S plus suitably distinguishing suffixes, may take any one of the well-known forms of 45 signaling devices provided with signal lamps having filaments, and as shown each signal S comprises a pair of signal lamps, designated by the 50 reference characters L plus suitably distinguishing suffixes, capable when energized to display a red indication. The lamps L of each signal S are adapted to be alternately flashed, in accordance 55 with the usual practice, at a rate of substantially thirty times per minute in response to an approaching train, to simulate the appearance of a horizontally swinging red lantern. As shown, preferably at least two signals S1 and S2 are provided at the intersection, and are located on opposite sides of the track for warning highway traffic approaching the intersection in either direction, of the approach of the train.

For the sake of simplicity and clearness in illustrating the circuits shown in Fig. 1 and hereinafter referred to as controlling each lamp L of the signals S, the lamps L are indicated in Fig. 1 as being located at the intersection on the signals S1 and S2, but the lamp filament for each 10 lamp is shown disposed in the control circuits in more advantageous positions from the viewpoint of tracing the circuits.

The reference character FN designates a flasher relay, by means of which the lamps L of signals S are adapted to be alternately flashed. The flasher relay may take different forms, but a preferred form is that disclosed in United States application for Letters Patent, Serial No. 156,549, filed July 30, 1937 by Benjamin Mishelevich for Electrical relays. Relay FN comprises in its essential elements two windings 4n and 4r, and a pivoted armature 5 operatively connected with insulated contact members 6, 7 and 8. Armature 5 is biased to a normal position, that is, the position shown 25 in Fig. 1, wherein contact members 6, 7 and 8 engage normal contacts 9, 10 and 11, respectively. When armature 5 is rotated in a manner described hereinafter, in a clockwise direction to its reverse position, the contact members 6, 7 30 and 8 engage reverse contacts 12, 13 and 14, respectively. Contact member 6 when in engagement with normal contact 9, shunts winding 4n and when in engagement with reverse contact 12 shunts winding 4r. Thus, with armature 5 35 in its normal position, when an energizing electromotive force is applied across the windings 4n and 4r, winding 4r is energized to attract armature 5 to rotate the armature in a clockwise direction so that normal contacts 6—9, 7—10 and 40 8—11 are opened, and reverse contacts 6—12, 7—13 and 8—14 are closed. This movement of armature 5 removes the shunt on winding 4n and closes the shunt on winding 4r so that winding 4r is deenergized, and winding 4n is energized to attract armature 5 into its normal position, thereby opening the reverse contacts, and closing the normal contacts. This cycle of operation is periodically repeated as long as the circuit for relay FN is closed, the parts being so 50 proportioned that an operating cycle is completed substantially every two seconds or thirty times per minute. As will appear more clearly hereinafter, the reverse contacts 7—13 and 8—14, and the normal contacts 7—10 and 8—11, of 55

relay FN serve to control the energizing circuits for lamps L of signals S, whereby the lamps L for each signal S are flashed alternately.

In order to permit trains approaching the intersection to control the operation of signals S, the track rails 1 and 1a are divided by means of the usual insulated rail joints 2 into track sections D—E and E—F which extend in opposite directions from the intersection. Sections D—E and E—F are provided with track circuits comprising in each instance a suitable source of current, such as track battery 3, connected across the track rails at one end of the section, and one winding W1 or W2 of an interlocking relay XR, connected across the track rails at the other end of the section. It is to be understood, of course, that while my invention as shown is applied to a signaling system governed by traffic controlled means, the scope of my invention is in no way limited to the specific control means shown but may be applied as well to signaling systems governed by manually operable control means.

In order to indicate a defect condition existing within the signals S, I provide an indicator, designated by the reference character K and herein shown as an electric lamp. The indicator K may be positioned wherever desired, such as, for example, along the tracks 1 and 1a so as to be visible to a maintainer riding the trains operating thereover, or in a maintainer's cabin.

The reference character KR designates an indication relay for controlling the indicator K. The relay KR is provided with a pick-up circuit governed by a manually operable push-button contact 15—16, and which circuit passes from one terminal B of a suitable source of current, such as a battery not shown, through push-button contact 15—16 and the winding of relay KR to the other terminal C of the source of current, and with a first stick circuit which may be traced from terminal B through front contacts 17 and 18 of relay XR, front contact 19 of relay KR and the winding of relay KR to terminal C. Preferably, the relay KR is provided with slightly slow releasing characteristics, which may be effected as shown by connecting a shunt resistor 20 across the terminals of its operating winding.

The reference characters LOR1 and LOR2 designate lightout relays connected in series with the lamp filament of each lamp L of signals S1 and S2, respectively. Relays LOR1 and LOR2 govern a second stick circuit for relay KR, which circuit may be traced from terminal B through front contact 21 of relay LOR1, front contact 22 of relay LOR2, front contact 19 of relay KR, and the winding of relay KR to terminal C.

When no trains are operating upon the control stretch of track intermediate the points D and F, the apparatus is in its normal condition, as shown in Fig. 1. In this normal condition, windings W1 and W2 of relay XR are energized, relay KR is held energized over its previously traced first stick circuit, and the relays FN, LOR1 and LOR2 are deenergized.

In describing the operation of the apparatus of Fig. 1, I shall first assume that each lamp L of signals S flashes properly during the operating period of relay FN, that is to say, the lamp filament for each lamp L of signals S is intact and remains intact as long as a train approaches the intersection. Under the above condition, when a train enters section D—E or E—F in approaching the intersection, the winding W1 or W2 of

relay XR included in the track circuit for the track section so entered is released to initiate the operation of signals S. For example, if section D—E is entered by an eastbound train approaching the intersection, the releasing of winding W1 of relay XR closes back contacts 23 and 24, and opens front contact 17. The closing of back contact 23 of winding W1 completes a circuit which may be traced from terminal B through back contact 23 of winding W1, and windings 4n and 4r of relay FN to terminal C, with the result that relay FN operates in the manner described hereinbefore. The closing of back contact 24 of winding W1 completes an energizing circuit for the lamps L of signals S, so that the operation of relay FN is effective to alternately flash the lamps of each signal S. That is to say, when back contact 24 of winding W1 is closed, and when the armature 5 of relay FN is operated to its normal position, the normal contacts 7—10 and 8—11 provide shunt paths around lamps L2 and L3 of signals S1 and S2, respectively, whereby those lamps are shunted and are thus deenergized, the lamps L1 and L4 of signals S1 and S2, respectively being energized to an illuminating condition over a circuit passing from terminal B through back contact 24 of winding W1, then through two branch paths to terminal C, one path of which includes the winding of relay LOR1, the filament of lamp L1, and normal contact 8—11 of relay FN; the other path of which includes the winding of relay LOR2, the filament of lamp L4 and normal contact 7—10 of relay FN. When the armature of relay FN is operated to its reverse position, the opening of normal contacts 7—10 and 8—11 removes the shunt upon lamps L2 and L3 whereby those lamps are energized to an illuminating condition, and the closing of reverse contacts 7—13 and 8—14 establishes a shunt upon lamps L1 and L4 whereby those lamps are deenergized and become dark, as can readily be understood from an inspection of the drawing. Relays LOR1 and LOR2, being interposed in the energizing circuits for lamps L1 and L2 of signals S1, and lamps L3 and L4 of signals S2, respectively, are each energized and held picked up during the interval that the associated signal lamps are operated to their alternately illuminating and non-illuminating conditions. It should be noted that since relay FN operates signals S1 and S2 by alternately shunting one or the other of the signal lamps of such signals, the relays LOR1 and LOR2 remain energized and picked up during the operation of contact members 7 and 8 of relay FN from their one position to the other. For example, during the interval contact member 8 of relay FN is operating from its normal (or right-hand) position to its reverse (or left-hand) position, relay LOR1 is then energized in series with the lamp filaments of both lamps L1 and L2 of signal S1. The filament of lamp L2 will at this time be in its "cold" condition wherein its resistance is relatively small with respect to the resistance of the filament of lamp L1 (which will be in its "hot" or illuminating condition) so that the energization of relay LOR1 at this time will be but slightly reduced and will still remain above its release value. Relay LOR2 will similarly be held energized and picked up during the operation of contact member 7 of relay FN from its one position to the other. Relays LOR1 and LOR2 are thus maintained picked up during the operation of signals S1 and S2, so that each relay closes its front contact 21 or 22 interposed

in the second stick circuit for relay KR to maintain that relay energized during the operation of signals S, the first stick circuit for relay KR now being open at front contact 17 of winding W1. It should be pointed out that the slow releasing feature of relay KR is effective to maintain its front contact 18 closed during the interval between the opening of the first and the closing of the second stick circuit for that relay. When the train vacates section D—E and winding W1 picks up, the operation of signals S and relay FN is terminated, so that relays LOR are released to open the second stick circuit for relay KR, which is now retained energized over its first stick circuit governed by the interlocking relay XR. It is apparent that since relay KR is maintained energized during the operating period of relay FN, the indicator K is controlled to display its normal indication both during the operating period of the signals S, and after the train vacates the control section D—E.

I shall now assume that the lamp filament of one or more lamps L of signals S failed or burned out during the just described operating period of relay FN. Under this latter condition of the apparatus, the lamp L having the failed filament will prevent the energization of its associated LOR relay during the period such lamp is controlled to its lighted condition. For example, assume that the filament of lamp L1 of signal S1 fails during the operating period of relay FN. In this event, relay LOR1 will be energized and picked up during the interval lamp L2 is illuminated by virtue of the shunt path established by contact 8—14 of relay FN around lamp L1. When, however, relay FN operates to open its contact 8—14, the shunt path around the failed filament of lamp L1, is then removed so that the circuit for relay LOR1 is open at that point and relay LOR1 becomes de-energized and releases. Relay LOR1 in releasing opens its front contact 21 interposed in the second stick circuit for relay KR, whereupon the latter relay in turn releases to control indicator K to its indication relating to a defective condition existing within signals S1 and S2. The release of relay KR also opens its front contact 19 which is common to both the first and second stick circuits for relay KR. Since front contact 19 of relay KR is open, the alternate picking up and releasing of relay LOR1 in response to its energization during the lighted period of the other lamp L2 of signal S1, is ineffective to control relay KR. Hence, since relay KR is released, when the train vacates section D—E the first stick circuit for that relay is open at front contact 19 of relay KR, with the result that relay KR remains released and indicator K continues to display its "defective" indication. It is readily apparent, therefore, that relay KR is maintained energized during the operating period of relay FN, and is conditioned for energization by the first stick circuit governed by the train controlled means after the operating period of relay FN, only in the event that each lamp L of signal S flashed properly in response to the operation of relay FN. Furthermore, relay KR once released remains released to control indicator K to register its "defective" indication until such time as the defective lamp is replaced by an intact lamp, and the push-button contact 15—16 is actuated by the maintainer to complete the pick-up circuit for relay KR, whereupon relay KR picks up to restore the apparatus of Fig. 1 to its normal condition.

An alternate arrangement for the apparatus of Fig. 1, wherein back contacts 26 and 27 of relays

LOR1 and LOR2, respectively, are connected in a third stick circuit for relay KR, is indicated in Fig. 1 by a dash line. In this alternative arrangement of Fig. 1, the third stick circuit including back contacts 26 and 27 of relays LOR1 and LOR2 serve to retain relay KR energized during the period that relay FN does not operate, and thus the first stick circuit for relay KR, which includes front contacts 17 and 18 of relay XR, may be dispensed with. The operation of the apparatus of the alternative arrangement of Fig. 1 is substantially similar to the operation of the apparatus of Fig. 1, as may readily be understood from an inspection of the drawings.

A further modification of the apparatus of Fig. 1 is shown in Fig. 2 wherein the pair of signal lamps, one for each signal S1 and S2, which are controlled at the same period to a lighted indication by means of the relay FN, are connected one pair each with relays LOR1 and LOR2. Lamps L4 and L2 are now energized in multiple over a circuit which may be traced from terminal B through back contact 24 or 36 of relay XR, the filament of lamp L4 in multiple with the filament of lamp L2, the winding of relay LOR2 and normal contact 7—10 of relay FN to terminal C. The circuit for lamps L1 and L3 now passes from terminal B through back contact 24 or 36 of relay XR, reverse contact 7—13 of relay FN, the winding of relay LOR1, and the filament of lamp L1 in multiple with the filament of lamp L3, to terminal C. The relays LOR now alternately control a second stick circuit for relay KR, which circuit now passes from terminal B through front contact 21 of relay LOR1 or front contact 22 of relay LOR2, front contact 19 of relay KR and the winding of relay KR to terminal C. Since the pairs of signal lamps are alternately flashed by means of the relay FN, the relays LOR1 and LOR2 are alternately energized and alternately complete the second stick circuit for relay KR during the operating period of relay FN. Each relay LOR1 or LOR2 is proportioned so that it will be energized and picked up only if both lamps of its associated pair of lamps are energized, but that when only one lamp of the associated pair of lamps is energized (the other lamp of the pair having a failed filament) the energy level created in relay LOR1 or LOR2 is insufficient to pick up that LOR relay and thereby complete for its alternating periods the stick circuit for relay KR. The failure of one LOR relay to pick up results in relay KR releasing during that period, to open its front contact 19 and thereby remove the other LOR relay, and the interlocking relay XR after the operating period of relay FN is terminated, from control of the indication relay KR and the indicator K. The indicator K now displays its "defective" indication, and will continue to do so until the pick-up circuit for relay KR is completed at push-button contact 15—16.

A further modification of Fig. 1 is shown in Fig. 3. In Fig. 3, relay KR is normally energized in series with the lamp filament of each lamp L of the signals S, over a circuit passing from terminal B through the filament of lamp L1, the filament of lamp L3, the winding of relay KR, front contact 23 of a relay TCR to be referred to later, the filament of lamp L4 and the filament of lamp L2 to terminal C. The winding of relay KR is preferably so proportioned that, in response to the current flowing in the just traced circuit, relay KR will be energized and picked up, but the filaments of the lamps L will not be energized sufficiently to be in their illuminating condition. The previ-

ously mentioned relay TCR serves as a repeater relay for winding W₁ or W₂ of relay XR, being normally energized over a circuit passing from terminal B through front contacts 29 and 30 of relay XR, and the winding of relay TCR to terminal C, and has back contacts one interposed in the energizing circuit for each lamp L, as may readily be understood from an inspection of the drawings, so that relay TCR when released completes the energizing circuit for the lamps L, whereby the operation of relay FN effects the alternate flashing of the lamps L of signals S. Relay TCR also has a front contact 28 interposed in the previously traced circuit for relay KR so that when relay TCR is released, relay KR is no longer energized over that circuit.

In the event, however, that relay KR is picked up over its previously traced circuit to close its front contact 19, relay KR is then conditioned to be retained energized when relay TCR is released and relay FN is operating, over a stick circuit which may be traced from terminal B through front contact 19 of relay KR, back contact 31 or 32 of relay XR, the winding of relay KR and back contact 33 of relay TCR to terminal C. If the lamps L of signals S flash properly during the operating period of relay FN, that is to say, if the lamp filament for each lamp L remains intact, then when the train vacates the control section D—E or E—F to terminate the operation of relay FN and to pick up the relay TCR, relay KR is then retained energized over its previously traced circuit including the lamp filament for each lamp of the signals S. If, however, a lamp filament burns out or fails during the operating period of relay FN, then relay KR can no longer be energized over the circuit including that lamp filament, so that after the train vacates section D—E or E—F and relay TCR picks up, relay KR releases to control indicator K to its "defective" indication. In the event that a lamp filament fails so that indicator K registers its "defective" indication, this indication is displayed until such time as the failed lamp has been replaced with an intact lamp, and when that happens, relay KR is then automatically re-energized over its circuit including each lamp filament, to pick up and control indicator K to its normal indication.

A second indicator K₁ is also shown in Fig. 3, and is controlled jointly by relay KR and by relay XR. The energizing circuit for indicator K₁ passes from terminal B through back contact 31 of relay KR, the filament of indicator K₁, and front contacts 33 and 34 of relay XR, to terminal C. In the event that relay KR is released due to a failed lamp filament, indicator K₁ will display its "defective" indication at all times except when winding W₁ or winding W₂ of relay XR is released by a train approaching the intersection. The "defective" indication of K₁ is then visible to a trainman or maintainer riding on the train operating over the control section of track when the train recedes from the intersection, or to a maintainer in his cabin at all times except when the train approaches the intersection.

Although I have herein shown and described only three forms of apparatus embodying my invention, it is to be understood that various changes and modifications may be made therein within the scope of the appended claims without departing from the spirit and scope of my invention.

Having thus described my invention, what I claim is:

1. In combination, a section of railway track intersected by a highway and provided with a track circuit including a track relay, a highway crossing signal located at said intersection and provided with a lamp filament, a normally energized indication relay, circuit means responsive to the condition of said lamp filament and controlled by said track relay under a first condition of that relay for energizing said indication relay provided that said filament is intact, stick circuit means governed by said track relay under a second condition of that relay for maintaining said indication relay energized, an indicator for indicating the integrity of said filament, and an energizing circuit for said indicator governed by said indication relay.

2. In combination, a section of railway track intersected by a highway and provided with a track circuit including a track relay, a highway crossing signal located at said intersection and provided with a lamp filament, a lightout relay, circuit means governed by said track relay under one condition of that relay and including the winding of said lightout relay for energizing said lamp filament, a normally energized indication relay, a first stick circuit governed by said lightout relay and being effective under said one condition of said track relay to maintain said indication relay energized provided that said filament is intact, a second stick circuit governed by said track relay and being effective under a second condition of that relay for maintaining said indication relay energized, and an indicator governed by said indication relay for indicating the integrity of said lamp filament.

3. In combination, a section of railway track provided with a track circuit including a track relay, a signal provided with a lamp filament, a lightout relay, circuit means governed by said track relay and including the winding of said lightout relay for energizing said signal when said section is occupied, a normally energized indication relay, a first stick circuit for said indication relay governed by said track relay and being effective to maintain said indication relay energized when said section is unoccupied, a second stick circuit for said indication relay governed by said lightout relay and being effective to maintain said indication relay energized when said section is occupied provided that said lamp filament is intact, and an indicator governed by said indication relay for indicating the integrity of said lamp filament.

4. In combination, a section of railway track provided with a track circuit including a track relay, a plurality of signals each provided with a lamp filament, a lightout relay for each signal, an energizing circuit for each signal governed by said track relay and including the winding of the associated lightout relay in series with the filament of that signal, an indication relay normally energized over a first stick circuit governed by said track relay and being effective to maintain said indication relay energized when said signals are deenergized, a second stick circuit for said indication relay serially including a front contact of each of said lightout relays and being effective to maintain said indication relay energized when said signals are energized only in the event that each said lamp filament is intact, and an indicator governed by said indication relay for indicating the integrity of said lamp filaments.

5. In combination, a section of railway track intersected by a highway and provided with a track circuit including a track relay, a highway crossing signal located at said intersection and provided with a lamp filament, an indication relay, a pick-up circuit responsive to said lamp filament and governed by said track relay to energize said indication relay when said section is unoccupied provided that said filament is intact, a stick circuit for said indication relay governed by said track relay for maintaining said indication relay energized when said section is occupied, and an indicator governed by said indication relay for indicating the integrity of said filament.

6. In combination, a section of railway track intersected by a highway and provided with a track circuit including a track relay, a highway crossing signal located at said intersection and provided with a signal lamp filament, an indication relay, a pick-up circuit for said indication relay serially including said lamp filament and being governed by said track relay to energize said indication relay when said track section is unoccupied, a stick circuit for said indication relay governed by said track relay to maintain said indication relay energized when said track section is occupied, an indicator for indicating the integrity of said lamp filament, and an energizing circuit for said indicator governed jointly by said indication relay and said track relay effective when said filament is failed to energize said indicator at all times except when a train occupies said section.

7. In combination, a stretch of railway track intersected by a highway, a track circuit for said stretch extending from said highway in the direction of approaching traffic and including

a track relay, two highway crossing signals located at said intersection, each said signal being provided with two signal lamps and each lamp having a filament, a first lightout relay connected in series with one lamp of each of said signals, said one lamps being connected in multiple with each other and said first lightout relay being so proportioned as to be energized to its holdup value only when both said one lamps are energized and their filaments are intact, a second 10 lightout relay connected in series with the other lamp of each of said signals, said other lamps being connected in multiple with each other and said second lightout relay being so proportioned as to be energized to its hold-up value only when both said other lamps are energized and their filaments are intact, a flasher relay, circuit means governed by said track relay for energizing said flasher relay when said section is occupied, circuit means governed by said track relay and said 20 flasher relay for causing said one and said other lamps to become alternately energized and de-energized when said section is occupied, an indication relay, a stick circuit for said indication relay completed over a front contact of said track relay for normally holding said indication relay energized, another stick circuit for said indication relay closed alternately at a front contact of said first or said second lightout relay according as said one or said other lamps are 30 energized and being effective to hold said indication relay energized when said section is occupied provided that the filament for each of said signal lamps is intact, and an indicator governed by said indication relay for indicating the integrity of the filaments of said signal lamps.

HENRY S. YOUNG.
